Inventor
Cyrus C. Boyer,

UNITED STATES PATENT OFFICE.

CYRUS C. BOYER, OF WATERLOO, INDIANA.

SWINGING GATE.

SPECIFICATION forming part of Letters Patent No. 427,148, dated May 6, 1890.

Application filed February 19, 1890. Serial No. 341,062. (No model.)

To all whom it may concern:

Be it known that I, CYRUS C. BOYER, a citizen of the United States, residing at Waterloo, in the county of De Kalb and State of Indiana, have invented a new and useful 5 Swinging Gate, of which the following is a specification.

The invention relates to improvements in swinging gates.

10 The object of the present invention is to provide a simple and inexpensive swinging gate adapted to be easily elevated to enable it to be passed over obstructions that may lie in its path, and that would otherwise prevent 15 its being opened.

The invention consists in the construction and novel combination and arrangement of parts, hereinafter fully described, illustrated in the accompanying drawings, and pointed 20 out in the claims hereto appended.

In the drawings, Figure 1 is a perspective view of a gate constructed in accordance with the invention and shown slightly elevated. Fig. 2 is a side elevation, partly in section.

25 Referring to the accompanying drawings, 1 designates a gate constructed in the usual manner and composed of the horizontal rails 2 and the vertical bars 3, arranged upon each side of the rails and located at the center and 30 ends of the gate. The gate is provided near its top with a rod 4, that extends horizontally along one of the rails 2, preferably the one next to the top of the gate, and has its inner end secured to the central vertical bars 3 by 35 means of a clip-plate 6, having a central perforation to receive the end of the rod 4, which is fastened with a nut to prevent withdrawal from said perforations. The other end 7 of the rod 4 is provided with an eye, which is en-

40 gaged by a suitable eye 8, extending from a vertical post 9, connected to a hinge-post 10 by eyes and pintles in the ordinary manner. When the gate is opened it swings upon said eyes and pintles 11; but when it is elevated 45 it moves upon the eye 8, extending from the vertical post 9, arranged between the gate and the hinge-post. In order to maintain the gate in an elevated position and enable it to be easily passed over snow-drifts or other 50 obstructions that may lie in its path, it is provided below the horizontal rod 4 with a pivoted rack-bar 12, that operates in a slot 13 of

the vertical bar 9, and is provided along its lower edge, near its outer end, with teeth 14, which are designed to engage a pin 15, secured 55 in said slot 13 and extending transversely in the same. The said pivoted rack-bar is operated by a cord 16, or the like, which is secured in a perforation of the rack-bar, and extends above the same and passes over a 60 pulley, and then along one of the horizontal rails 2, and is connected to an operating-lever 18, pivoted at its lower end to one of the rails 2, and extending above the next higher rail within easy reach of a person desiring to open 65 the gate. This lever is designed to be drawn toward the free end of the gate to raise the pivoted rack-bar 12 and bring one of the outer teeth 14 into engagement with the transverse pin 15 to maintain the gate in an ele- 70 vated position. The upper end of the operating-lever 18 is guided in its movement by a suitable keeper 19.

From the foregoing description and accompanying drawings the construction, operation, and advantages of the invention will 75 readily be seen.

The gate is guided in its movements vertically and prevented from swinging laterally by the lower rail, which projects beyond the 80 gate and forms an extension 20, working in a recess at the end of the vertical bar 9.

What I claim is—

1. The combination of the vertical bar 9, designed to be hinged to a suitable post, the 85 gate secured near its upper end to said bar, and the rack-bar pivoted to the gate and arranged to engage the bar to maintain the gate in an elevated position, substantially as described.

2. The combination of the bar 9, designed to be hinged to a post, the gate secured near its upper end to the bar, the rack-bar pivoted to the gate and arranged to engage the said bar, and the operating-lever pivoted to the 95 gate and connected with the rack-bar and adapted to raise the same, substantially as and for the purpose described.

3. The combination of the vertical bar 9, designed to be hinged to a post and provided 100 with a transverse recess, and having a pin 15 arranged therein, the gate secured near its upper end to the bar, the rack-bar pivoted to the gate, operating in the slot of the vertical

bar and engaging the pin 15, and the operating-lever connected with the pivoted rack-bar, substantially as and for the purpose described.

5 4. The combination of the vertical bar 9, provided near its upper end with an eye 8 and near its lower end with a slot 13, and having a pin 15 arranged transversely therein, the gate provided near its upper end with a 10 horizontal rod 4, having an eye 7 engaging the eye 8 of the vertical bar 9, and the rack-

bar pivoted to the gate and arranged to engage the pin 15, and operated by suitable means, substantially as and for the purpose described.

In testimony that I claim the foregoing as my own I have hereto affixed my signature in presence of two witnesses.

CYRUS C. BOYER.
